(57) CLAIM

The ornamental design for elements of a front fairing for a snowmobile, as shown and described.

DESCRIPTION

FIG. 1 is a perspective illustration, from the front and left side, of elements of a front fairing for a snowmobile according to my design;

FIG. 2 is a left side elevation view thereof, the right side being a mirror image;

FIG. 3 is a front elevation view thereof;

FIG. 4 is a rear elevation view thereof;

FIG. 5 is a top plan view thereof; and,

FIG. 6 is a bottom plan view thereof.

In FIGS. 1, 3, 5 & 6, broken lines showing structure are for illustrative purposes only and form no part of the claimed design.
